US0D1009048S

(12) **United States Design Patent** (10) **Patent No.:** **US D1,009,048 S**
(45) **Date of Patent:** ** *Dec. 26, 2023

(54) **RECORDING AND DATA STORAGE MEDIA**

(71) Applicant: **Giesecke+Devrient Mobile Security GmbH**, Munich (DE)

(72) Inventor: **Alexander Summerer**, Rimsting (DE)

(73) Assignee: **GIESECKE+DEVRIENT MOBILE SECURITY GMBH**, Munich (DE)

(*) Notice: This patent is subject to a terminal disclaimer.

(**) Term: **15 Years**

(21) Appl. No.: **29/808,673**

(22) Filed: **Sep. 22, 2021**

(30) **Foreign Application Priority Data**

Mar. 31, 2021 (DE) 40 2021 100 302

(57) **CLAIM**

The ornamental design for a recording and data storage media, as shown and described.

DESCRIPTION

FIG. 1 is a top view of a recording and data storage media. FIG. 2 is a bottom view of the recording and data storage media of FIG. 1.

FIG. 3 is a left view of the recording and data storage media of FIG. 1.

FIG. 4 is a right view of the recording and data storage media of FIG. 1.

FIG. 5 is a rear view of the recording and data storage media of FIG. 4.

FIG. 6 is a front view of the recording and data storage media of FIG. 1; and,

FIG. 7 is a perspective view of the recording and data storage media of FIG. 1.

The broken lines illustrate supplementary environmental structure of the recording and data storage media and form no part of the claimed design depending on the drawing views.

1 Claim, 7 Drawing Sheets
